UNITED STATES PATENT OFFICE.

ORMA N. FARNHAM, OF SANISH, NORTH DAKOTA.

SPRING BED.

1,426,972.

Specification of Letters Patent. Patented Aug. 22, 1922.

Application filed June 14, 1922. Serial No. 568,199.

To all whom it may concern:

Be it known that I, ORMA N. FARNHAM, a citizen of the United States, residing at Sanish, in the county of Mountrail and 5 State of North Dakota, have invented new and useful Improvements in Spring Beds, of which the following is a specification.

This invention relates to a spring bed, and the object is to provide particular means for 10 increasing the tension of certain of the springs.

A further object is to provide means for increasing the tension of the springs extending centrally and longitudinally of the 15 bed, when weight is applied on both sides of the central portion of the bed and on the springs there located.

A still further object is to provide a series of elements extending longitudinally 20 and each including a coiled spring, or springs and tension wires, the wires being connected with a stationary element at one end of the bed, and a plurality of pivotally mounted elements with which several of the 25 wires and springs on both sides of the central longitudinal axis are connected, the pivotally mounted members acting to cause the tensioning of the wires immediately adjacent to the longitudinal axis, when weight is applied to the wires and the springs connected 30 with the pivotally mounted members on opposite sides of the pivotal point.

With the foregoing and other objects in view, the invention consists in the novel 35 construction, combination and arrangement of parts hereinafter described and claimed, it being understood that modifications may be made within the scope of the claims without departing from the spirit of the invention.

In the drawings:—

Figure 1 is a top plan view of the bed and

Figure 2 is a section on the line 2—2 45 of Figure 1.

The transverse members of the bed are designated 10 and 12, these elements being directly connected by several wires and tension springs, at the side portions of the bed. 50 The longitudinal side bars are shown at 13 and 14, the wires immediately adjacent

thereto are designated 15 and the springs connected with these wires are designated 16.

Other wires 17 are connected with the 55 springs 18 on both sides of the central longitudinal axis, a number of wires and springs being designated by the same reference number or numbers.

The wires are connected directly with the 60 end member 12 for the full length thereof, but the wires 17 are connected with pivoted arms or levers 20 or 21, as the case may be. The levers are fulcrumed by the means of 65 the pins 23, which enter the central apertures 24 in the levers or enter one of the other apertures 25 somewhat removed from the center, so that the leverage may be varied as the circumstances may require. Apertures are formed in the end member 10 70 corresponding with the apertures in the levers, in order that the change of position may be made as required.

When weight is applied to the springs and wires on the outer side of the pivotal 75 point of a given lever, the wires and springs on the other side of the pivotal point will be tensioned automatically. In order to more definitely define the construction, the wires between the springs and the end member 10 are designated 15 and 17, and those between the springs and end member 12 are designated 15' and 17'. In another sense 80 each spring and the wires connected directly therewith, constitute a single tension 85 element.

What is claimed is:—

1. In a spring bed, a plurality of end members, side bars connecting said members, pivotally mounted elements carried by 90 the end members near the central portion thereof, resilient elements connected with the pivotally mounted members between the pivotal points and the central longitudinal axis of the bed, and means imparting movement to 95 the pivotally mounted members for increasing tension on said resilient elements.

2. In a spring bed, a plurality of end members, side bars connected therewith, pivotally mounted levers mounted on one of said end 100 members near the middle portion thereof and normally extending parallel with the

end member last named, tension devices including wires and coiled springs extending longitudinally between the side members, permanently connected with one of the end members, and connected with the pivoted element on opposite sides of the pivotal points thereof, and mounting means for the

pivoted element permitting of change in the position of the fulcrum point of the respective levers. 10

In testimony whereof I affix my signature.

ORMA N. FARNHAM.
